Primary Examiner — Susan Moon Lee

CLAIM

The ornamental design for an oral care implement, as shown and described.

DESCRIPTION

FIG. 1 is a right front perspective view of an oral care implement according to the new design; FIG. 2 is a left front perspective view thereof; FIG. 3 is a right rear perspective view thereof; FIG. 4 is a left rear perspective view thereof; FIG. 5 is a front view thereof; FIG. 6 is a rear view thereof; FIG. 7 is a right side view thereof; FIG. 8 is a left side view thereof; FIG. 9 is a top view thereof; and, FIG. 10 is a bottom view thereof.

The broken lines shown in the drawings depict environmentally illustrative portions of the article that form no part of the claimed design.

1 Claim, 5 Drawing Sheets

Related U.S. Application Data

division of application No. 29/488,927, filed on Apr. 24, 2014, now Pat. No. Des. 770,183, which is a division of application No. 29/444,030, filed on Jan. 25, 2013, now Pat. No. Des. 706,036, which is a division of application No. 29/358,641, filed on Mar. 30, 2010, now Pat. No. Des. 676,245.
